Howson & Howson

UNITED STATES PATENT OFFICE.

LEMBERT H. MOULTHROP, OF PHILADELPHIA, PENNSYLVANIA, ASSIGNOR TO H. T. PAISTE COMPANY, OF PHILADELPHIA, PENNSYLVANIA, A CORPORATION OF PENNSYLVANIA.

SWIVEL CONNECTION.

1,255,774.

Specification of Letters Patent.

Patented Feb. 5, 1918.

Application filed December 8, 1915. Serial No. 65,796.

To all whom it may concern:

Be it known that I, LEMBERT H. MOULTHROP, a citizen of the United States, residing in Philadelphia, Pennsylvania, have 5 invented Swivel Connections, of which the following is a specification.

One object of my invention is to provide a simple, compact and inexpensive device for so connecting a cover and a base structure,—and more particularly the cap and part of the body of a socket,—as will permit of the relative rotation or swiveling of said parts;—the invention also contemplating the provision of means whereby said parts may be rigidly clamped together.

I further desire to provide means for detachably connecting a cover and a base structure, which may be adjusted either to movably connect said parts so as to permit 10 their relative rotation or to immovably clamp them together.

These objects and other advantageous ends I secure as hereinafter set forth, reference being had to the accompanying drawings, 15 in which:

Figure 1 is a detached perspective view illustrating my invention as designed for use with or as part of a porcelain socket; and

Fig. 2 is a vertical section of the socket top and cap shown in Fig. 1.

In the above drawings, 1 represents a structure of vitreous material such as porcelain, made in the shape of a flattened cylinder and in the present case constituting the top member of a porcelain lamp socket, whose body, forming no part of the present invention, is omitted. This member has a central passage 2 and a hollow 3 of larger 35 volume opening into the same in which are customarily mounted terminals for the attachment of electric conductors passing through the opening 2. Said conductors are also constructed to be attached to certain apparatus in the socket but as they constitute no part of the invention they also have been omitted.

The upper face of the structure 1 is normally covered by a cap 4 made of a dished body of sheet material having a central opening for the reception of a relatively thick internally threaded metal bushing 5 and likewise having its upper edges formed with an inwardly extending flange 6. The

porcelain structure 1 which serves as a 55 base for the cap or cover 4 has an annular plane surface for engagement with the flange 6 which is held in place thereon by a pair of clamping plates 7 respectively engaged by screws 8 threaded into 60 them preferably adjacent their central points. The heads of these screws are counter sunk in shouldered channels formed in the porcelain base 1 and it is noted that the cap-covered face of said base has two 65 oppositely disposed recesses 9 whose bottom portions are on the level of the surface designed for engagement by the flanges 6.

The plates 7 enter said recesses 9 and are so proportioned that when their outer ends 70 rest upon the flange 6, their inner ends likewise rest upon the bottoms of the recesses. The openings in which the screws 8 are mounted are preferably inwardly flared as they approach and enter the recesses 9 re- 75 spectively, so that when the screws have been sufficiently backed off, they may be made to assume positions with their axes in converging lines instead of parallel as shown in Fig. 2. At such time the clamping plates 80 7, which are arranged radially of the base or socket structure 1, are moved toward the center line of said structure with their outer edges withdrawn from engagement with the flange 6.

Obviously therefore, when the parts occupy such positions or are capable of occupying them, it is possible for the cap to be freely removed. Thereafter when said cap is applied to the base, the screws 8 may be 90 set up sufficiently to draw the plates down to the seats provided by the bottoms of the recesses 9 and the flange 6, whereupon said screws naturally assume the parallel positions shown in Fig. 2. The cap 4 is thus 95 held to the base 1 although it may be freely rotated relatively thereto in the manner necessary to screw its threaded bushing 5 onto the threaded end of a conduit. Thereafter by further setting up the screws 8 the plates 100 7 may be drawn down to clamping engagement with the flange 6, thereby immovably holding the cap to the base and preventing its further relative rotation.

If desired the device may be permanently 105 left in a condition allowing the swiveling of the cap or cover on the base, which may with it constitute a complete article of manu-

facture or be connected to or used as part of some electro-receptive device, as a socket.

I claim:

1. The combination of a base structure; a cover therefor having a flange lying substantially parallel with and adjacent a portion of the structure; and separate retaining members on opposite sides of the base structure engaging said flange so as to permit relative 10 rotation of the cover and the base structure.

2. The combination of a base structure of insulating material; a flaring metal cover therefor having an inwardly extending flange at its larger end and mounted with 15 said end engaging said structure; with radially extending clamping plates mounted on the base in position to loosely engage the flange and allow relative rotation of the cover and base.

20 3. The combination of a base structure; a cover for said structure having an inwardly extending flange engaging the same; separate clamping plates mounted on the base and loosely extending over the flange; with 25 screws adjustable to cause the plates to removably clamp the flange to the base.

4. The combination of a base structure having screw holes therein; a cover having a flange and mounted on the base; a plurality 30 of structurally independent clamping plates

engaging the flange; and screws extending through said holes into the clamping plates.

5. The combination of a base structure having screw holes therein; a cover having a flange mounted on the base; clamping plates 35 engaging the flange; and screws extending through said holes into the clamping plates; said screws being laterally movable in their respective holes to permit the plates to move into or out of engagement with the flange of 40 the cover.

6. The combination of a base structure having flaring holes therein; a cover mounted on said structure and having an internal flange; plates inclosed by the cover and engaging the base and flange; with screws extending upwardly through the holes in the base into the plates and laterally movable in the wider portions of said holes to allow 45 said plates to move into or out of engagement with the flange.

7. The combination of a base structure having flaring holes therein; a cover mounted on said structure and having a flange; plates mounted to engage the flange; with 50 screws extending through said holes in the base into the plates and movable in the wider portions thereof to allow said plates to move into or out of engagement with the flange.

LEMBERT H. MOULTHROP.
